UNITED STATES PATENT OFFICE.

JOHN PIERCE, JR., OF SOUTH NORWALK, CONNECTICUT, ASSIGNOR OF ONE-HALF TO
DICKINSON S. CUMMINGS, OF STAMFORD, CONNECTICUT.

STEAM-BOILER.

1,345,231.

Specification of Letters Patent. Patented June 29, 1920.

Application filed February 13, 1920. Serial No. 358,513.

To all whom it may concern:

Be it known that I, JOHN PIERCE, Jr., a citizen of the United States, and a resident of South Norwalk, in the county of Fairfield and State of Connecticut, have invented new and useful Improvements in Steam-Boilers, of which the following is a specification.

My invention relates to steam boilers and more particularly to a light weight high pressure type for use in automobiles, aeroplanes or steam yachts.

One object of the invention is to construct a boiler having the greatest heating surface in a given space.

Another object is to provide for the generation of drier steam by producing a boiler having a low steam contact with the water.

Another object is to prevent water entering the steam drum when the boiler is placed at an angle as when an automobile is on a hillside or a yacht is rolling in a heavy sea.

Another object is to construct a boiler having high thermo efficiency and perfect circulation under all conditions.

A further object is to produce a high pressure boiler having the right proportions of water and steam for fast steaming.

A still further object is to provide means whereby any of the headers and connected tubes may be easily removed and replaced.

Other objects and advantages will be apparent as the description proceeds.

35 In the accompanying drawings:

Figure 1 is a front elevation of the boiler, parts being broken away;

Fig. 2 is a side elevation of the same;

Fig. 3 is a top plan view;

40 Fig. 4 is a fragmentary rear elevation, parts being shown in cross section;

Fig. 5 is a detail section of one of the headers showing the angular relation of the bent ends of the tubes welded thereto.

45 Fig. 6 is an enlarged fragmentary view of one of the sections;

Fig. 7 is a detail view of one of the connections between the steam drum and headers.

50 Referring to the drawings, a feed water intake pipe 1 is shown connected to one end of a feed water distributing drum 2 located

at the bottom or intake end of my improved boiler.

In order to distribute the water rapidly and uniformly to the entire boiler, I construct the same of a number of sections 3, each section comprising a complete unit consisting of a vertical tubular header 4 and steam generator tubes 5. Ten sections are shown in the drawings but any number may be used, depending upon the horse power of the engine to be driven. As the sections are identical in construction the description of one will suffice for all.

65 The vertical tubular headers 4 are connected to the feed water distributing drum 2 by the short sections of tubing 6 and 8 welded thereto at their opposite ends after the latter and demountably connected at 70 their abutting ends by the high pressure unions 7.

65 Mounted at the highest point on the boiler is a steam drum 9 extending the full width thereof and connected to the top of the 75 headers 4 by the short sections of tubing 10 and 12 and a high pressure union 11 similar to the one 7 above described.

In order to feed, to the engine the hottest and driest steam possible, I place a steam 80 discharge pipe 13 at the highest point in the steam drum 9, so that the steam under pressure at this point can pass through openings 14 in the steam discharge pipe 13 and through said pipe 13 to the engine not 85 shown in the drawings.

The steam generator tubes 5 are formed of a single piece of seamless steel tubing bent to form a loop, one end being welded to the header at 15 and the other end at 16. 90 The point 16 being higher than the point 15, the loop 17 is consequently disposed at an angle to the vertical header 4. The angles of curvature indicated by the reference letter A in Fig. 5, represent the angle of 95 least resistance to the circulation of water and steam. The curvature of the ends of the tubes 5 also to lock said ends are placed in the proper openings 18 in the vertical headers, prior to welding.

100 To prevent any strain being placed on the generator tubes 5 and their connections to the vertical headers 4 I provide depending hangers 18 bolted at their upper ends as at

19 to a horizontally disposed I beam 20 secured to the boiler casing, not shown; and in properly spaced relation to one another are tube supporting stirrups 21 designed to 5 take up all vertical vibration of the tubes.

Some of the heat applied to the boiler will pass directly up through the space 22 between the tubes 5 until it reaches a baffle plate 23, when it will be deflected to the 10 adjacent section. The baffle plates are made of a suitable heat resisting material and are placed in staggered relation throughout the boiler so as to obtain all of the heat possible from the fire.

15 In operation my boiler is simple and efficient. Water is fed in through the feed water intake 1 to the feed water distributing drum 2 and is in turn fed to the headers where it rises to the level indicated by the reference 20 letter L. The water level L gives the right proportion of water for fast steaming (13½ gallons to 160 sq. ft.) and is kept at this level by suitable injectors not shown. By 25 opening the feed water distributing drum the entire contents of the boiler can be discharged, thus flushing the tubes, the headers and the feed water distributing drum of all sediment deposited therein.

A boiler constructed as illustrated will 30 have the highest possible thermo efficiency, as will be seen as the description proceeds. My boiler has a greater heating surface in a given space than any boiler of its type. Heat is applied to the boiler in the usual 35 way and passes upward as shown by the arrows in Fig. 2, around the baffle plates 23 and out at the top. The baffle plates 23 retard the progress of the heat upward passing it to the next section and giving it a 40 rolling action throughout the boiler, thus giving the tubes a chance to absorb as much of the heat as possible. The heat then passes under the steam drum 9, around the unions 11 and the tops of headers 4 and 45 finally to the atmosphere. As the heat passes around unions 11 and the tops of headers 4 it further heats the steam, thus reducing the possibility of moist steam reaching the steam discharge pipe 13.

50 A perfect circulation of water is made possible by the particular angle at which the generator tubes are placed in relation to the headers 4, this angle is indicated in Fig. 6 by the reference letter B. In this connection it will be stated that as the water passes 55 from the header into the lower leg of each of the tubes, it is heated and passes back and into the headers by way of the upper leg of each tube. The vaporized product passing 60 from the latter rising in the header while that part of the water not heated sufficiently to vaporize will drop or fall and thereby again circulate through the tubes. Thus the water will circulate through the various 65 tubes until it has been vaporized and that

the quality of the heated products will be free from moisture. The circulation is also aided by the provision of tubes having the same size inner bore free from sharp angles or projections of any kind. This increased 70 circulation not only aids fast steaming but tends to prevent sediment settling in the tubes.

The generator tubes 5 above the water line L contain only steam which is fully 75 dried and superheated by the action of heat against said tubes giving a higher pressure than obtainable by methods used in the past. A low steam contact with the water is due to the arrangement of headers 4 and generator tubes 5 as illustrated, further aiding the 80 production of dry steam and as the steam is not in direct contact with the main body of water saturation is prevented. The steam drum 9 is placed high enough to prevent 85 water entering when the car is on a hillside at any angle. I have provided the steam discharge pipe 13 to take the steam from the highest point in the steam drum 9 which is supplied from the various sections 3, thus 90 equalizing the pressure throughout the system and minimizing the tendency of an engine to prime or draw water from the boiler.

95 My boiler sections 3 are demountable and interchangeable at all times so that quick repairs may be made without removing boiler from car. Any of the sections 3 may be removed for repairs by unscrewing the unions 7 and 11 and if desired pipes leading 100 thereto may be plugged and the boiler operated as before without decreasing the efficiency or power of the remaining sections.

In assembling my boiler I prefer to use 105 seamless steel tubing of high tensile strength for my feed water distributing drum, headers and steam drum with their ends plugged and welded as illustrated. The generator tubes are also of seamless steel tubing properly annealed before and after bending. 110 The angle indicated by the letter A in Fig. 1 serves a double purpose; that of aiding the circulation and also as a locking means for holding the tube in position while being welded.

115 It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention, what I claim as new and desire to secure and protect by Letters Patent of the United States, is:

120 In a steam generator, a horizontally disposed water distributor head, a steam drum arranged above the distributor head and in 125

parallel relation thereto, a plurality of parallel vertical headers communicating with the distributor head and steam drum, a plurality of horizontally disposed U-shaped circulating tubes communicating with each of the vertical headers, the planes through the legs of the U-shaped tubes being disposed at an oblique angle to the horizontal

and parallel to each other, one leg of each tube being secured to the header at a point 10 between the legs of the adjacent tube, so that the unvaporized products passing from the upper leg of each tube will fall and pass into the lower leg.

JOHN PIERCE, Jr.
